[57] CLAIM

The ornamental design for a ring having a body and a rotatable central ring, as shown and described.

DESCRIPTION

FIG. 1 is a perspective view of a ring having a body and a rotatable central ring showing my new design;

FIG. 2 is a top plan view thereof, the bottom plan view thereof being identical thereto;

FIG. 3 is a view thereof from the top of FIG. 2, the view from the bottom of FIG. 2 being identical thereto;

FIG. 4 is a view thereof from the left of FIG. 2, the view from the right of FIG. 2 being identical thereto;

FIG. 5 is a view similar to FIG. 2 but showing the central ring in a different position;

FIG. 6 is a left-side view of FIG. 5, the right-side view of FIG. 5 being identical thereto;

FIG. 7 is a view similar to FIG. 2 but showing the central ring in a third position; and,

FIG. 8 is a left-side view of FIG. 7, the right-side view of FIG. 7 being identical thereto.
